Patented Mar. 2, 1965

200,470

COMBINED TELEVISION TRANSMITTER AND TELEPHONE

Edward L. Byer, Fort Wayne, Ind., and John Cuccio,
Westport, Conn., assignors to International Telephone
and Telegraph Corporation, Nutley, N.J., a corporation
of Maryland

Filed Feb. 6, 1964, Ser. No. 78,625

Term of patent 14 years

(Cl. D26—14)

Fig. 1

Fig.2

FIGURE 1 is a perspective view of a combined television transmitter and telephone showing our new design; and

FIGURE 2 is a perspective view of the combined television transmitter and telephone of FIGURE 1 with the side panels lowered and the telephone deleted for clarity of illustration.

The dominant features of our new design are shown in solid lines in the drawing.

The top and back are substantially flat surfaces and unornamented.

We claim:

The ornamental design for a combined television transmitter and telephone, as shown and described.
